ELECTRICAL SWITCH

Stephen J. Roesch and Joseph W. Myers, Philadelphia, Pa., assignors to Proctor & Schwartz, Inc., Philadelphia, Pa., a corporation of Pennsylvania

Application March 4, 1942, Serial No. 433,394

18 Claims. (Cl. 200—4)

This invention relates to electric switches, and more particularly to a novel switch structure adapted to perform certain functions as described hereinafter. The invention is not limited to any particular use of the switch structure and, therefore, it is to be understood that the switch structure provided by the invention may be employed for control purposes in any instance where it is capable of use. However, the invention is directed particularly to the control of electric ranges and it will be described with reference to this specific application.

The objects or purposes of the invention, as well as certain illustrative forms thereof, may be more clearly understood by first considering certain recently developed features of the electric range art with which the present invention is particularly concerned. To impart to an electric range unit a speed of initial heating comparable to that of a gas unit, it has been found desirable to provide suitable "flashing" means for greatly increasing the energization of the electric range unit until the desired temperature level has been reached and then automatically restoring the normal energization of the unit. The flashing operation is performed by switching circuit connections of the range unit. An example of a flashing device of this character is disclosed and claimed in the Myers and Roesch Patent No. 2,207,634, granted July 9, 1940.

It is also desirable in some instances to provide a manually-adjustable thermostatic control device for an electric range unit, which device is responsive to the temperature of a cooking vessel placed on the unit and operates the unit at the desired temperature level. Such device has been aptly termed a "pan control device." A device of this specific character is also disclosed in the above-mentioned patent, as well as in the Myers and Roesch Patent No. 2,140,479, granted December 13, 1938, which is directed particularly to such a device.

It is also desirable to provide multiple heats for an electric range unit in order that the unit may be operated at different temperature levels, such as "low," "medium," and "high," corresponding to the different levels of operation of a gas unit. Further, it may be desirable to prevent flashing of the range unit at certain temperature levels, i. e. when the multiple heat control switch is operated to certain positions corresponding to said levels. This feature is also disclosed in the first-mentioned Myers and Roesch patent.

With regard to an electric range as a whole, it is desirable to prevent overloading due to flash-

ing, and this may be accomplished by dropping a portion of the load during the flashing of one of the units. Such a system is disclosed and claimed in the Myers Patent No. 2,213,993, granted September 10, 1940. The load-dropping may be effected by opening one of the supply conductors during the flashing of a unit, thus preventing energization of subsequent units connected to the supply conductors. Since it is convenient to use a single switch for the flashing of a unit and the dropping of subsequent load, it is necessary that the switch be in its normal position whenever the associated unit is turned "off." If the switch were permitted to be in its flash position when the unit is turned off, it would be impossible to operate the subsequent units owing to the load dropping feature.

With respect to flashing generally, it is also desirable to provide means for preventing accidental or deliberate prolonging of the flash connections, which would result in damage or destruction of the particular heating unit.

In some instances, it is also desirable to employ a heating unit comprising two concentric rings and to provide for operation of one or both of said rings, as shown generally in the Myers and Roesch Patent No. 2,140,479.

By the present invention, there is provided a novel switch structure which is particularly adapted to meet the above-mentioned requirements of modern developments in the electric range art, and which is capable of a variety of uses and has other advantages and desirable features.

In a broad sense, without reference to any particular usage, the primary object of the invention is to provide a novel switch structure by which different circuit conditioning functions may be effected, particularly where it is desired to automatically terminate the connections for one circuit conditioning function and to establish the connections for another circuit conditioning function, as in the case of an electric range having provision for flashing one or more of the units thereof.

Another object of the invention is to provide a unitary switch which will permit the selection of certain circuit connections and will also permit certain other circuit connections to be established at will irrespective of said first connections, and to provide means for terminating the second connections and reestablishing the first connections at a desirable point in a control cycle.

A further object of the invention is to provide

a unitary switch adapted to permit a plurality of normal circuit connections, selectable at will, and also to permit a special circuit connection at will, and to provide means for terminating said special circuit connection under certain conditions, and for preventing the establishment of said special circuit connection under certain conditions.

Still another object of the invention is to provide a unitary switch which is adapted to perform the various control functions which are desired in an electric range, as set forth above, said switch being adaptable to operation as a unitary flash and normal energization control switch, as a multi-heat control switch, as a control device for a pan control thermostat, and as a control device for a two-ring unit.

Other objects and features of the invention will be apparent hereinafter.

In the accompanying drawings:

Fig. 1 is a plan view of one form of the switch provided by the invention;

Fig. 2 is a side elevation of the same;

Fig. 3 is a bottom view of the switch;

Fig. 4 is a rear view of the switch;

Fig. 5 is a sectional view taken along line 5—5 of Fig. 1;

Fig. 6 is a sectional view taken along line 6—6 of Fig. 5;

Fig. 7 is a similar sectional view showing the parts in different position;

Fig. 8 is a perspective view of the mechanism by which the flashing operation and other functions may be performed;

Figs. 9 to 12 are perspective views of certain parts of the device;

Fig. 13 is a fragmentary perspective view of certain parts;

Fig. 14 is a perspective view similar to Fig. 8 showing the illustrated mechanism in a different condition;

Fig. 15 is a sectional view taken along line 15—15 of Fig. 5;

Fig. 16 is a sectional view taken along line 16—16 of Fig. 5;

Fig. 17 is a perspective view of a certain part of the device;

Fig. 18 is an electrical diagram showing the switch in conjunction with a pan control thermostat and the heating unit being controlled;

Figs. 18A and 18B show the positions of the switch contacts at different times;

Fig. 19 is a sectional view similar to Fig. 5 of a different form of the switch;

Fig. 20 is a rear view of the same;

Fig. 21 is an electrical diagram showing the application of this form of the switch for multi-heat and flash control;

Figs. 21A to 21D show the different positions of the switch contacts;

Fig. 22 is a plan view of a further form of the switch;

Fig. 23 is a side elevational view of the same;

Fig. 25 is a sectional view taken along line 25—25 of Fig. 24;

Fig. 26 is a fragmentary perspective view of a part; and

Fig. 27 is an electrical diagram showing the switch of Figs. 22 to 26 in conjunction with a two-ring heating unit.

Referring first to Figs. 1 to 4 of the drawings, the switch shown therein is encased in a box or casing 1, made of suitable insulating ma-

terial, which is enclosed on all but one side. For manufacturing and assembly purposes, the casing 1 may be split longitudinally, and may comprise two sections 2 and 3 held together by bolts 4. It will be noted that the contour of the parts 2 and 3 is such as to permit ready and accurate positioning thereof.

On the top of casing 1 there are terminal lugs 5 held fixedly thereto by virtue of fitting into slots 6, and secured by rivets 7 which may also serve to connect the said lugs electrically to the contact elements within the casing, to be described presently. Cooperatively associated with the lugs 5 are screws 8, which are adapted to permit connection of wires from the external circuits to the lugs 5.

On the bottom of casing 1 are located lugs 9 (see Fig. 3) fixedly positioned by contoured recesses 10 and rivets 11 which also serve to connect the lugs 9 to certain of the switch elements. Cooperatively associated with the lugs 9 are screws 12 which are adapted to permit connection of wires from the external circuits to the lugs 9.

On the front of casing 1 there is secured a mounting bracket 13, preferably of metal, having suitable provision for attachment to an electric range, so as to hold the switch in proper position on the range. A drip cover 13a (see Figs. 4 and 5) may be provided to protect the terminal lugs 5 from spillage.

At the top of the front of the casing 1 is located a pilot light socket 14 connected mechanically and electrically to an extension 15 on one of the front lugs on the top of casing 1. In this socket is shown pilot light 16. A wire 17 completes the electrical connection of the light socket and extends to another lug, as shown.

On the open side of the casing 1, is attached a plate 18 carrying mechanism important to the flashing operation which will be described in detail later. Within casing 1 (Fig. 6) are located stationary contacts 19 and flexible contact blades 20. These parts are arranged substantially to the right of the casing, as viewed in Figs. 6 and 7, so as to leave sufficient space to accommodate the flashing mechanism presently to be described. The contacts 19 are fastened to the top of the insulated casing and are electrically connected to lugs 5 by the rivets 7. The blades 20 are fastened to the bottom of the casing at 21 and are electrically connected to lugs 9 by rivets 11. The blades are arranged so that they are normally biased by their own resilience to make contact with the right hand contacts 19 (left hand contacts in Figs. 6 and 7). Also located within casing 1 (Fig. 5) are connecting buses such as 22 and 23, which serve to interconnect various blades, contacts and connection lugs.

Located at the front of casing 1 and formed integrally with the base thereof is a stop 24. This stop (see Fig. 13) comprises portions 25, 26, and 27 adapted to cooperate with the flange 28 of a cam member 29 (Figs. 10 and 12) carried by the operating shaft 30. The several portions of stop 24 serve different purposes, as will be described later. On the front of cam member 29 are located several radial depressions 32 adapted to act cooperatively with a detent 33 on a plate 34 (Figs. 10 and 11), so as to snap the switch into various selected positions and hold it in such positions until other positions are chosen, as will be more apparent later. The plate 34 has its side edges seated in

grooves 35 (Figs. 5 and 13) formed in the side walls of casing 1, and is thus held in fixed position adjacent the front wall. An opening 36 in the plate 34 accommodates the shaft 30. Operating shaft 30 has at its front end a knob 37 (Fig. 5) which may be employed to effect the various operations of the shaft. Knob 37 may have suitable indicia (not shown) associated with it to indicate angular positions of the knob in terms of control of an associated heating unit. It will be noted that shaft 30 has a hollow section 38 (Figs. 5 and 10) which is hexagonal in section and thus shaft 30 is adapted to be slidably mounted over a hexagonal cam shaft 39 extending through casing 1. At the front end of shaft 30 is a threaded portion 40 which receives bolt 41 for securing knob 37 to the shaft. Rotation of the knob on the shaft may be prevented in any known manner, for example by making the engaging portions non-circular or by providing cooperating flat surfaces on said portions. Within the hollow portion of shaft 30 is placed a compression spring 42 designed to press against the internal shoulder 43 and against the head of a bolt 44 extending through shaft 39. A second compression spring 45 presses against the head of bolt 44 and the end of shaft 39. Thus, springs 42 and 45 tend at all times to urge shaft 30 to its outermost position, as shown in Fig. 5.

Mounted on the rear of casing 1 and passing through an opening in the rear wall is a bushing 46 having an axial bore 47 to receive an external shaft, as described further hereinafter, screw 48 serving to fix the shaft in a definite angular relation to the bushing. A portion of bore 47 is threaded to receive the threaded end of bolt 44, and a set screw 49 fixes the position of bushing 46 relative to bolt 44. At its forward end, shaft 39 fits into and is positioned by the hexagonal bore of member 29. At its rearward end, shaft 39 fits into a circular recess of bushing 46, which serves to position and center it. The springs 42 and 45 maintain the parts in the positions shown in Fig. 5, and spring 45 maintains the rear end of shaft 39 in frictional engagement with the recessed end of coupling 46, thus maintaining the relative angular position of shaft 39 and coupling 46 constant, unless adjustment is made as described later. In shaft 39 is an opening 50 through which fits a pin 51 integral with bolt 44. Positioned on shaft 39 are cams 52 adapted to operate blades 20. The rearmost cam 52a is adapted to engage an extension 53 of the flashing mechanism, for a purpose which will be evident later.

Plate 18 carries the flashing mechanism, which is best shown in Figs. 8 and 14. Turned ears 54 on plate 18 form supports for a shaft 55. On this shaft there are rotatably mounted two L-shaped plates 56 and 57 having turned mounting ears 58 and 59. These plates carry indented insulating pieces 60 and 61 shaped to fit blades 20. The insulating piece 61 carried by plate 57 is adapted to operate only the first or foremost blade, while the insulating piece 60 operates the other blades in unison. A tab 62 on plate 56 is adapted to be engaged by plate 57 in order that the latter may actuate plate 56 in a counter-clockwise direction, as viewed in Figs. 8 and 14. Attached to plate 57 is a finger 63 which extends outwardly from plate 57 substantially parallel to the top portion thereof and has a down turned lip 64 adapted to be engaged by the conical portion of member 29. Also on

plate 56 is an upturned lug 65 to which is pivotally attached a member 66 of an over-center latching mechanism. The member 66 is pivotally attached to member 67 of the latching mechanism, which in turn is attached rotatably to a lug 68 on plate 18 (see Figs. 6 and 7). Member 67 has a stop portion 69 adapted to act cooperatively with a stop 70 on plate 18, and a cam portion 71 adapted to be engaged by an adjustable latch tripping member 72 in the form of a screw on the end of a bimetallic member 73.

The bimetallic member 73 (see Fig. 2) is attached by rivets 74 to a supporting bracket 75 preferably formed of metal. Bracket 75 is supported on plate 18 by means of rivet 76 and porcelain bushings 77. A heating element 78 (see Fig. 17) is disposed between insulating sheets 79, preferably of mica, adjacent to the bimetal member 73. This heater may be wrapped with asbestos cord 80 (Fig. 2) so as to heat and cool substantially similarly to the heating unit being controlled by the switch, as disclosed in the aforementioned Myers and Roesch Patent No. 2,207,634. The asbestos cord may also assist in holding the heater and the insulating sheets in place. The heating element is connected to screw terminals 81 which are insulated from plate 18 by the porcelain bushings 77 and the mica sheets 79. Connector strips 82 connect the terminals 81 to the same lugs 5 to which the pilot light 16 is connected.

In operation of the switch to control a heat-unit, the shaft 30 is rotated clockwise from its "off" position (by knob 37) to effect various degrees of normal energization of a heating unit being controlled. The degree of normal energization may be obtained for example by utilization of coupling 46 to operate, by means of flexible shafting, a cam on a pan control thermostatic device such as is disclosed in the aforementioned Myers and Roesch Patent No. 2,140,479, or in the copending Myers application Serial No. 380,341, filed February 24, 1941.

Referring specifically to the flashing operation, when knob 37 is pushed inward, shaft 30 is caused to slide along shaft 39 until flange 28 of cam member 29 comes into contact with portion 25 of stop 24. During this movement of shaft 30 the conical member 29 engages lip 64 on finger 63, thereby causing plate 57 to rotate about shaft 55 in a counter-clockwise direction as may be seen in Fig. 16. By virtue of tab 62, plate 56 is also rotated simultaneously and is latched into flashing position by latch members 66 and 67, as shown in Fig. 7. When the two members 56 and 57 are thus rotated, the blades 20 are moved into contact with the left hand contacts 19. However, the first blade (shown in Fig. 16), when thus actuated simply engages an insulating strip 83 and prevents energization of the unit until knob 37 is released. Thus, so long as the knob 37 is held in, the unit is automatically deenergized. Consequently, it is impossible to flash the unit excessively and thus damage the unit by manually holding the knob 37 in its innermost position. However, when knob 37 is released, the shaft 30, by virtue of spring 42, is forced back to its normal position. Cone 29 is thus disengaged from finger 63, and plate 57 then rotates back into its normal position under the force exerted by the resilience of first contact blade. Thus, the first blade returns to engage its right-hand contact 18, and the unit is energized. The remainder of the blades 20,

however, are maintained in the left-hand position, and in such position make connections to flash the unit. As the flashing of the unit progresses, the bimetal member 73 is heated and flexes, forcing latch tripping member 72 into engagement with cam portion 71 (see Fig. 7) and eventually pushing pivot 84 into a position where its center is above the line of centers of pivots 85 and 86. In this position, the members 66 and 67 can no longer hold member 56 in place, and it snaps back into its normal position under the force of the resilient spring members 20. Thus, the resilient spring members 20 resume their normal energization positions as previously selected by the rotation of knob 37.

If now, it should be attempted to reflash the unit, it would be found that this could not be done, as the bimetal member 73 is in a position to prevent latch members 66 and 67 from latching plate 56 in position. Since no flash is obtained when the knob 37 is held in its innermost position, and since the plates 56 and 57 now rotate counter-clockwise (as viewed in Figs. 6 and 7) to their normal positions upon the release of knob 37, no flash can take place.

If the switch is actuated to cause a flash of the unit, and if for some reason it is desired to turn the unit off before the flash is completed, this can be done. Whenever knob 37 is rotated to the "off" position, the cam 52a engages extension 53 of latch member 66, and moves the member out of latching position. It is thus obvious that whenever the unit is turned off, any incompletely flashed will be cleared by this means. This is an advantage should the operator unintentionally initiate a flash on the wrong unit. Furthermore, where the switch drops the subsequent load, as will be described presently, this self-clearing means prevents the operator from accidentally leaving the switch in flash position with the associated unit turned off.

The adjustment screw 72 is provided to allow the duration of the flashing time to be adjusted. It is obvious that the time of flashing will depend on how far the bimetal element 73 has to move before the head of the screw engages portion 71 of member 67. By adjustment of the screw, its head can be moved closer to or farther from portion 71, thus effecting a change in the flashing time.

Referring to the stop 24 (Fig. 13), portion 27 thereof acts cooperatively with extension 31 (Figs. 10 and 12) on flange 28 to limit the rotation of knob 37, in its selection of normal energization, to an arc less than 360°. Portion 26 of stop 24 acts cooperatively with extension 31 to prevent sliding movement of shaft 30 when the knob 37 is in the "off" position. This prevents movement of the switch to flash position when it is off, thereby preventing accidental dropping of the subsequent load. Portion 25 of stop 24 acts cooperatively with flange 28 to limit the sliding movement of shaft 30 during the flashing operation.

In use with a pan control thermostat, it may be found necessary at times to readjust the relative position of the knob 37 and the coupling 46, in order to make the indications of the knob 37 follow correctly the actual values obtained. However, it is undesirable to change the position of knob 37 relative to shaft 39, as the off position will be determined by the cams on shaft 39, and the position of operation of the detent means is determined by shaft 30, which is rotatably fixed with regard to shaft 39. The desired adjustment

may be effected as follows. The screw 41 may be removed from the front of knob 37. Then a screw driver may be placed inside hollow shaft 30, and engage the head of bolt 44. If knob 37 is held, and the screw 44 is rotated, adjustment may be made within the limits of travel of pin 51 in opening 50 in shaft 39. For ease of adjustment, the adjustment should be made in one of the detent-operating positions, which may be easily set and maintained.

The above-described form of the switch is adapted for use in conjunction with a pan control device and its operation may be more clearly understood with the aid of the electrical diagram of Fig. 18. In that figure there is illustrated diagrammatically at 81 a pan control device of the type disclosed in the above-mentioned Myers application Serial No. 380,341, and the heating unit being controlled comprises two main sections 88 and 89 and a low-wattage heating element 90, which are controlled by the pan control device in the manner set forth in the said application. The details of construction of the particular pan control device and its specific mode of operation in conjunction with the particular heating unit are not of importance here and need not be illustrated or described. It suffices to state that the particular pan control device diagrammatically illustrated in Fig. 18 is merely illustrative of any device of that general type in which a thermostatic switch controls the heating unit. If desired, a simple form of such device, such as that disclosed in the above-mentioned Patent No. 2,207,634, could be used. From the foregoing description, it will be understood that the pan control device will be adjustable for operation of the heating unit at various temperature levels by means of a flexible shaft connected to the coupling member 46 of the present switch, so that rotation of knob 37 will effect the desired adjustments of the pan control device.

The main sections 88 and 89 of the heating unit are connected in parallel across the outer conductors of the supply line 91 for flash operation and are connected in series across said conductors for normal operation. Fig. 18 shows the position of the contact blades of the switch in the "off" position, the first and last blades (left to right) being held in the positions shown by the cams 52, as shown in Fig. 15. The fourth blade engages load dropping contacts. Fig. 18A shows the position of the contact blades in the "on" position, cams 52 permitting the first and last contact blades to move to their right hand positions. Fig. 18B shows the position of the contact blades in the flash position, the blades having been actuated by the flashing mechanism. The series and parallel connections of the main heating unit sections for normal and flash operations may readily be seen from Figs. 18A and 18B with reference to Fig. 18. It will be noted that in this instance in which the normal energization of the heating unit is controlled by means of a pan control device, the contact blades merely serve to turn the heating unit on or off and to effect the flash connections.

In the operation of the switch as thus adapted, whenever the knob 37 is rotated from the off position, the contact blades are immediately actuated to turn the heating unit on, the blades then being in the position of 18A. Further rotation of the knob 37 does not change the positions of the 75 blades but adjusts the pan control thermostat

through the flexible shaft connection as above described.

Whenever it is desired to flash the heating unit, the knob 37 is depressed which causes the contact blades to move to the positions of Fig. 18B. The flashing operation may be performed irrespective of the position of knob 37 throughout its range of normal energization control. When the knob is depressed to initiate the flashing operation, the first contact blade is held open, as indicated by the broken line illustration, by plate 57 until the knob is released, as above described, thereby preventing excessive flash of the heating unit. During the flashing operation, the lowermost supply conductor is opened by the fourth contact blade, thereby dropping the subsequent load.

It should be noted that the pilot light 16 is connected in parallel with the heating element 78 for the flash release thermostat, and these elements are in series with the heating unit 88-89 during normal operation and in series with one section or leg of the unit during flash operation. Consequently, during normal operation, the pilot light 16 will glow dimly to show that the unit is in operation, while during flash operation the light will glow brightly as the voltage across the heating element 78 will be twice as much during flash as during normal energization. Of course, care should be exercised to employ a pilot light which will withstand the higher voltage during flash operation.

In Figs. 19 and 20, the switch is slightly modified to effect various degrees of normal energization by means of the switch cams, as illustrated in Figs. 21 to 21D. In this embodiment, the switch structure is essentially the same as before, but the cams 52 are designed and arranged to effect the desired function. There is also provided a more positive means for retaining the switch in the different control positions.

At the rear end of shaft 39, there is provided a sleeve 92 corresponding generally to the coupling sleeve 48 of the previously-described device, and adapted to rotate with shaft 39. A square cam 93 is affixed to sleeve 92 by means of a pin 94. An arm 95 is hinged to the rear of casing 1 at 96 and is urged into engagement with the cam 93 by a spring 97 which is anchored to the casing at 98.

In the off position of the switch, one of the flat sides of cam 93 is engaged by arm 95 so as to establish the off position, as illustrated in Fig. 20. When the control knob is rotated to turn the heating unit on, the cam 93 moves the arm 95 against the action of spring 97 until the next adjacent flat side of the cam is engaged by the arm, thereby establishing the "low" normal energization position. Further rotation of the knob establishes the "medium" and "high" positions of the switch. Since in this instance the switch must operate through 360°, the stop member 24 should be modified accordingly. This merely requires omission of portion 27 thereof. The flashing operation is performed in the same manner as previously described.

In the previously described embodiment, flash operation of the switch in its off position is prevented by the coaction of parts 26 and 31 as hereinbefore described. In the device of Figs. 19 and 20, flash operation of the switch may also be prevented in certain other positions of the switch merely by proper design of the same parts. For example, it may be desired to prevent flash operation at the "low" position, in which case

the parts 26 and 31 of elements 24 and 29 may be designed accordingly. This would merely require extension of part 26 to prevent longitudinal movement of shaft 30 in the low position as well as in the off position.

Aside from the above-mentioned differences, the structure illustrated in Figs. 19 and 20 is similar to the first-described embodiment and requires no further description.

10 Figs. 21 to 21D illustrate the operation of the modified switch to provide a plurality of heats by variously connecting the heating unit 88-89 to the supply conductors. In Fig. 21, the contact blades are shown in the "off" position. In Fig. 21A, the contact blades are shown in the position for "low" operation, and both sections of the heating unit are connected in series between the uppermost and central conductors, between which there may be a voltage of 115 15 volts compared to 230 volts across the two outer conductors. In Fig. 21B, the contact blades are shown in the position for "medium" operation in which section 88 only of the heating unit is connected between the uppermost and central conductors. Fig. 21C shows the position of the contact blades for "high" operation during which both sections of the heating unit are connected in series across the two outer conductors.

Fig. 21D shows the position of the contact blades for flash operation during which both sections of the heating unit are connected in parallel across the two outer conductors and the subsequent load is dropped.

In the utilization of the switch as described 35 immediately above, three principal cams are required, as shown at 52 in Fig. 19, and of course the cams must be designed to position the contact blades in the manner illustrated in Figs. 21 to 21D for various positions of the control knob 40 37.

45 In Figs. 22 to 26, there is illustrated a further modification of the switch structure for the control of a heating unit comprising two concentric rings, as previously mentioned. In this adaptation of the switch, the flashing operation of the unit is dispensed with and the mechanism previously employed for that purpose is utilized to switch from one ring operation to two ring operation, as will be described in detail presently.

50 Referring to the mechanical structure of the switch, the construction is substantially the same as that first described, except for certain changes to adapt the device for the desired control. The bimetal element previously described to terminate the flashing operation is eliminated but the heating element 78 is retained and serves simply as a resistance element in parallel with the pilot lamp 16. Accordingly, the heating element 78 may comprise a flat strip of resistance wire secured between mica sheets 79 carried by bracket 75 18.

Further in this embodiment of the device, the plate 51 is modified as shown in Fig. 26 and this plate serves merely to actuate plate 56 since, as stated above, the flashing operation is dispensed with.

As before, plate 56 is latched in its actuated position by the latching means 68-69 which is released by cam 52a when the control knob is turned to the off position. Thus, in this instance, the latching means for plate 56 is released only by cam 52a.

In this instance there are two cams 52 for operating the first and last contact blades between on and off positions.

The operation of this form of the device may best be understood with the aid of Fig. 27 in which there is shown a multi-section heating unit which is intended to be a diagrammatic illustration of a two ring unit such as above mentioned. The inner ring may comprise sections 99 and 100 while the outer ring may comprise sections 101 and 102. The pan control device 87 is again employed to vary the normal energization level. In this instance also the heating unit includes auxiliary low wattage sections 103 and 104 associated respectively with the inner and outer rings. Here again the specific form of the pan control device is not important, and this device could be of the simple form previously mentioned.

When the switch is in off position, as shown in Fig. 27, the blades are in the position shown. When the control knob is rotated from the off position, the cams 52 of Fig. 24 cause the first and last blades to engage their associated contacts, thereby connecting sections 99 and 100 in series between the two outer conductors of the supply line. The rotation of the control knob also adjusts the pan control device in the manner previously described.

When it is desired to use the entire heating unit, the control knob is pushed inward and plate 57 moves the other blades into engagement with their associated contacts, thereby connecting sections 101 and 102 in parallel with sections 99 and 100, respectively. As mentioned above, plate 57 is latched in its actuated position until the switch is returned to off position. Rotation of the control knob, with the entire heating unit energized, adjusts the pan control device to establish any desired operating level of the unit.

Referring to the invention generally, it will be seen that the switch is adapted to perform different functions in response to different modes of operation. Thus in the first two forms described, rotation of the control knob conditions the circuit connections of the associated heating unit for normal energization and also establishes different temperature levels either by adjusting a pan control device or by effecting different connections, while depression of the control knob conditions the circuit connections for flash operation. In the last described form of the switch, depression of the control knob conditions the circuit connections for operation of the entire heating unit, while rotation of the knob controls the energization of the unit and also the temperature level.

From the foregoing description, it will be seen that the switch is capable of various uses and is adapted to perform various control functions. Moreover, the circuit diagrams illustrated and described are merely illustrative of some of the uses and adaptations of the switch and are in no way intended to disclose all of its possible applications.

The illustrated embodiments of the switch are, of course, only illustrative and are not intended to limit the scope of the invention.

We claim:

1. In an electrical switch, a plurality of relatively movable contacts, means for supporting said contacts in mutually cooperative relation, a manual operating member arranged for rotational and translational movement, means operable by translational movement of said member for effecting relative movement of said contacts to effect a circuit conditioning function, means for automatically retaining the relative positions

5 of said contacts established by said last means, and means for releasing said retaining means in response to rotation of said member to a predetermined position.

2. In an electrical switch, a plurality of relatively movable contacts, means for supporting said contacts in mutually cooperative relation, a manual operating member arranged for rotational and translational movement, means operable by translational movement of said member for effecting relative movement of said contacts to effect a circuit conditioning function, means for automatically retaining the relative positions of said contacts established by said last means, and thermal-responsive means for automatically releasing said retaining means after a time interval.

3. In an electrical switch, a plurality of relatively movable contacts, means for supporting said contacts in mutually cooperative relation, a manual operating member arranged for rotational and translational movement, means operable by translational movement of said member for effecting relative movement of said contacts to effect a circuit conditioning function, means for automatically retaining the relative positions of said contacts established by said last means, thermal responsive means for automatically releasing said retaining means after a time interval, and means for releasing said retaining means at will in response to rotation of said member to a predetermined position.

4. In an electrical switch, a plurality of relatively movable contacts, means for supporting said contacts in mutually cooperative relation, a manual operating member, means operable by said member for effecting relative movement of said contacts to effect a circuit conditioning function, and means for preventing the completion of said circuit conditioning function until said member is released.

5. In an electrical switch, a plurality of relatively movable contacts, means for supporting said contacts in mutually cooperative relation, a manual operating member arranged for rotational and translational movement, means operable by rotational movement of said member for actuating said contacts so as to effect a circuit conditioning function, means operable by translational movement of said member for actuating said contacts so as to effect a different circuit conditioning function, and means for preventing the completion of said last-mentioned circuit conditioning function until said member is released.

6. In an electrical switch, a plurality of relatively movable contacts, means for supporting said contacts in mutually cooperative relation, a manual operating member arranged for rotational and translational movement, means operable by rotational movement of said member for actuating said contacts so as to effect a circuit conditioning function, means operable by translational movement of said member for actuating said contacts so as to effect a different circuit conditioning function, and means for preventing translational movement of said member when it is in a certain position of rotation.

7. In an electrical switch, a plurality of stationary contacts, means for supporting said contacts, a plurality of movable contacts, means for supporting said movable contacts in cooperative relation with said stationary contacts, a manual operating member arranged for rotational and translational movement, means operable by rotational movement of said member for actuating at

least some of said movable contacts to effect a circuit conditioning function, means operable by translational movement of said member for actuating at least some of said movable contacts to effect a different circuit conditioning function, means for latching the movable contacts in the position to which they are actuated by said last means, and means for releasing said latch means when said member is in a certain position, thereby to terminate the last-mentioned function.

8. In an electrical switch, a plurality of stationary contacts, means for supporting said contacts, a plurality of movable contacts, means for supporting said movable contacts in cooperative relation with said stationary contacts, a manual operating member arranged for rotational and translational movement, means operable by rotational movement of said member for actuating at least some of said movable contacts to effect a circuit conditioning function, means operable by translational movement of said member for actuating at least some of said movable contacts to effect a different circuit conditioning function, means for latching the movable contacts in the position to which they are actuated by said last means, means for automatically releasing said latch means after a time interval to terminate the last-mentioned function, and means for releasing said latch means at will in response to rotation of said member to a predetermined position.

9. In an electrical switch, a plurality of stationary contact elements, means for supporting said elements, a plurality of resilient contact blades, means for supporting said blades in cooperative relation with said elements, a rotatable shaft arranged cooperatively with said blades, means on said shaft for actuating predetermined ones of said contact blades to effect at least one circuit conditioning function, a manual control member for rotating said shaft and movable axially of the shaft, and means operable by the axial movement of said member for actuating predetermined ones of said contact blades to effect another circuit conditioning function.

10. In an electrical switch, a plurality of stationary contacts, means for supporting said contacts, a plurality of movable contacts, means for supporting said movable contacts in cooperative relation with said stationary contacts, a rotatable shaft arranged cooperatively with said movable contacts, means operable by said shaft to actuate at least some of said movable contacts and thereby effect a circuit conditioning function, a member movable axially of said shaft, means operable by said member to actuate at least some of said movable contacts to effect a different circuit conditioning function, means for latching the movable contacts in the position to which they are actuated by said last means, and means for releasing said latch means when said shaft is in a certain position, thereby to terminate the last-mentioned function.

11. In an electrical switch, a plurality of stationary contact elements, means for supporting said elements, a plurality of resilient contact blades, means for supporting said blades in cooperative relation with said elements, a rotatable shaft arranged cooperatively with said blades, means on said shaft for actuating predetermined ones of said contact blades to effect at least one circuit conditioning function, a manual control member for rotating said shaft and movable axially of the shaft, means operable by the axial movement of said member for actuating pre-

5 termined ones of said contact blades to effect another circuit conditioning function, means for latching the contact blades in the position to which they are actuated by said last means, and means for automatically releasing said latch means after a time interval to terminate the last-mentioned function.

12. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to effect at least one circuit conditioning function, a manual control member for rotating said shaft and movable axially of the shaft, means operable by the axial movement of said member for actuating predetermined ones of said contact blades to effect another circuit conditioning function, means for latching the contact blades in the position to which they are actuated by said last means, and thermal responsive means for automatically releasing said latch means after a time interval to terminate the last-mentioned function.

13. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to effect at least one circuit conditioning function, a manual control member for rotating said shaft and movable axially of the shaft, means operable by the axial movement of said member for actuating predetermined ones of said contact blades to effect another circuit conditioning function, means for latching the contact blades in the position to which they are actuated by said last means, and means for releasing said latch means when said shaft is in a certain position, thereby to terminate the last-mentioned function.

14. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to effect at least one circuit conditioning function, a manual control member for rotating said shaft and movable axially of the shaft, means operable by the axial movement of said member for actuating predetermined ones of said contact blades to effect another circuit conditioning function, an over-center latching mechanism for latching the contact blades in the position to which they are actuated by said last means, and cam means on said shaft for releasing said latching mechanism when said shaft is in a certain position, thereby to terminate the last-mentioned function.

15. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to ef-

fect at least one circuit conditioning function, a manual control member for rotating said shaft and movable axially of the shaft, means operable by the axial movement of said member for actuating predetermined ones of said contact blades to effect another circuit conditioning function, means for latching the contact blades in the position to which they are actuated by said last means, and means for preventing axial movement of said member when said shaft is in a certain position of rotation.

16. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to effect at least one circuit conditioning function, a manual control member for rotating said shaft and movable axially of the shaft, means operable by the axial movement of said member for actuating predetermined ones of said contact blades to effect another circuit conditioning function, and means for preventing the completion of said last-mentioned circuit conditioning function until said manual member is released.

17. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating pre- 30

35 determined ones of said contact blades to effect at least one circuit conditioning function, a manual control member for rotating said shaft and movable axially of the shaft, a pivoted member arranged cooperatively with predetermined ones of said contact blades and adapted to actuate the said blades to effect another circuit conditioning function, and means including a cam on said control member for actuating said pivoted member in response to axial movement of the control member.

18. In an electrical switch, a plurality of stationary contact elements, means for supporting said elements, a plurality of resilient contact blades, means for supporting said blades in cooperative relation with said elements, a rotatable shaft arranged cooperatively with said blades, a plurality of cams on said shaft for actuating predetermined ones of said contact blades to effect at least one circuit conditioning function, a manual control member for rotating said shaft and movable axially of the shaft, a pivoted member arranged cooperatively with predetermined ones of said contact blades and adapted to actuate the said blades to effect another circuit conditioning function, means including a second pivoted member operable by axial movement of said control member to actuate said first pivoted member, and means operable by said second pivoted member to prevent completion of said last-mentioned circuit conditioning function until said control member is restored to its normal axial position.
